(57) **CLAIM**

The ornamental design for a toy skateboard, as shown and described.

DESCRIPTION

FIG. 1 is a front perspective view of an ornamental design for a toy skateboard in accordance with the invention;

FIG. 2 is a left side bottom perspective view of FIG. 1;

FIG. 3 is a left side view of FIG. 1;

FIG. 4 is a right side view of FIG. 1;

FIG. 5 is front side view of FIG. 1;

FIG. 6 is a rear side view of FIG. 1;

FIG. 7 is a top side view of FIG. 1; and,

FIG. 8 is a bottom side view of FIG. 1.

The broken lines are for environmental purposes only and form no part of the claimed design.
